(57) **CLAIM**

The ornamental design for a blender user interface, as shown and described.

DESCRIPTION

FIG. 1 is a left perspective view of a blender user interface, showing my new design.

FIG. 2 is a front view of the blender user interface of FIG. 1.

FIG. 3 is a back view of the blender user interface of FIG. 1.

FIG. 4 is a left side view of the blender user interface of FIG. 1.

FIG. 5 is a right side view of the blender user interface of FIG. 1.

FIG. 6 is a top view of the blender user interface of FIG. 1; and,

FIG. 7 is a bottom view of the blender user interface of FIG. 1.

The purpose of the broken lines shown in the drawings is to illustrate portions of the article that form no part of the claimed design.

1 Claim, 7 Drawing Sheets
